UNITED STATES PATENT OFFICE.

EDGAR M. SCRANTON, OF ROCHESTER, NEW YORK, ASSIGNOR OF ONE-HALF TO CLARENCE W. MCKAY, OF ROCHESTER, NEW YORK.

PASTE-BOX AND DAUBER.

No. 888,756.

Specification of Letters Patent.

Patented May 26, 1908.

Application filed August 14, 1907. Serial No. 388,463.

To all whom it may concern:

Be it known that I, EDGAR M. SCRANTON, of Rochester, in the county of Monroe and State of New York, have invented certain new and useful Improvements in Paste-Boxes and Daubers; and I do hereby declare the following to be a full, clear, and exact description of the same, reference being had to the accompanying drawings, forming a part 10 of the specification, and to the reference-numerals marked thereon.

My present invention relates to receptacles for paste and similar viscous materials in combination with means for removing small 15 quantities of the latter therefrom for application to the uses for which they are intended, and it has for its object to provide a convenient and efficient device of this nature suitable for the reception of shoe polish or leather 20 dressings, which will prevent the deterioration of such substances when confined therein and which may be manufactured at a sufficiently low cost to be furnished at a moderate price, as the container for the polish in 25 offering the latter for sale.

Further objects of my invention are to provide a construction through the employment of which all of the paste or polish may be readily utilized and the operation of its 30 removal rendered clean and attractive.

To these and other ends the invention consists in certain improvements and combinations of parts all as will be hereinafter more fully described, the novel features being 35 pointed out in the claims at the end of the specification.

In the drawings: Figure 1 is a perspective view of the paste containing receptacle; Fig. 2 is a similar view of the stopper and dauber 40 therefor; Fig. 3 is a vertical central section of the complete device, and Fig. 4 is a top plan view thereof.

As before indicated, my invention is particularly, though not exclusively, useful as 45 applied to containers for the viscous or plastic dressing commonly used for polishing shoes and I will refer to it herein for convenience in this connection. The polish is usually supplied in cans or boxes having removable covers and applied to the leather by means of a separate brush or dauber, but the box cover is often lost or misplaced, allowing the contents to become dry, dusty and unfit for use and the dauber after having 50 been used will become similarly affected and

require a careful disposition to prevent it from soiling other objects. The cover in such receptacles generally has a definite fixed position out of contact with the polish, so that when a portion of the latter has been used there is formed an air chamber between the polish and cover which allows the contents to become quickly dry, destroying its usefulness to a large extent and rendering its removal and successful application difficult. In addition to this, the dauber and receptacle are often of widely different relative sizes, for proper co-operation, with the result that when the dauber is too large a portion only of the polish in the receptacle can be 60 reached thereby, and when too small, unused portions are apt to be left remaining upon the side walls and in the angles of the bottom, particularly if the latter is not secured steadily in place, and be discarded with the box. 65 To overcome these and other disadvantages, I provide a cylindrical receptacle with a sliding stopper fitting within the chamber thereof, having a projecting handle portion on the top and material constituting a dauber on 70 the bottom adjacent the polish, the face of the dauber conforming both in contour and extent to that of the bottom of the chamber, so that the paste may be applied to the dauber by a relative twisting movement of 75 the assembled members as long as a particle 80 of material remains.

Referring more particularly to the drawings, 1 indicates a suitable cylindrical box or receptacle, the chamber therein being open at one end and closed at the other by preferably flat bottom 2 and containing a quantity of polish 3. The chamber is preferably of uniform cross sectional area, its sides being smooth and continuous. Fitted to slide vertically therein is a stopper 4, of sufficient thickness to prevent it from becoming jammed through lateral tilting and provided on its upper side with a handle 5, smaller in diameter than the chamber and preferably of sufficient length to project through the open end of the latter at all times. Secured to the under side of the stopper is a dauber 6 comprising in the present instance a flat pad of felt or similar fibrous material, its under surface conforming to and being co-extensive with the bottom of the receptacle. The handle, stopper and pad may be secured together with cement or glue, but it is preferable to form a tenon 7 upon the handle 5 110

projecting within an opening in the stopper, a headed pin or staple 8 being driven through the pad or dauber into the tenon portion of the handle.

5 It will be seen that the stopper, dauber and receptacle thus form practically one element and may be conveniently kept assembled for ready use. In operation, the receptacle is held by one hand and the handle of 10 the stopper by the other and a relative twisting movement imparted to either, whereat the dauber is scraped across the surface of the polish, the adhering portions being applied as usual. By continued use, the dauber 15 will ultimately reach the bottom and being of the same area therewith, will remove every particle of the contents resulting in great economy of material.

As the stopper fits closely within the 20 straight walls of the box or receptacle, it slides downwardly as the quantity of polish is diminished, bringing the dauber which forms virtually an air tight packing, always in contact with the latter and preventing its 25 hardening from exposure to the air, while the projecting handle forms a convenient grasp and by reason of its relatively small diameter does not crowd the fingers of the operator when the contents are very low. 30 Conversely the particles remaining on the dauber after use are preserved in good condition for subsequent operations and a device constructed in accordance with my invention, may be advantageously designed with 35 a receptacle of greater depth than is usual to render handling more convenient and cleanly.

I claim as my invention:

1. The combination with an open recep-

tacle, of a stopper therefor fitting within the receptacle provided with a dauber on its 40 under side having a lower surface conforming to that of the bottom of the receptacle.

2. The combination with a cylindrical receptacle open at one end, of a circular dauber having yielding edges fitting within said receptacle and a lower surface coextensive with and conforming to that of the bottom 45 of the receptacle.

3. The combination with a cylindrical receptacle of uniform cross sectional area, of a 50 stopper adapted to contact with the walls thereof throughout the length of the latter and having a dauber arranged on its under side.

4. The combination with a receptacle open 55 at one end and having uniform cross sectional area, of a stopper fitting within the receptacle and movable throughout the length thereof having a dauber arranged on its under side and a handle on the stopper of 60 smaller diameter than the receptacle and accessible through the opening therein.

5. The combination with a cylindrical receptacle of uniform cross sectional area and adapted to contain a viscous material, of a 65 stopper fitting within the receptacle and having a dauber arranged on its underside adjacent the material in the receptacle, said dauber comprising a pad of fibrous material conforming in area and contour to the bottom 70 of the receptacle, and a handle on the stopper.
